Chas B. Mann

UNITED STATES PATENT OFFICE.

WILLIAM S. TILGHMAN, OF WORCESTER COUNTY, MARYLAND.

FODDER-HOLDER.

SPECIFICATION forming part of Letters Patent No. 256,931, dated April 25, 1882.

Application filed February 25, 1882. (No model.)

To all whom it may concern:

Be it known that I, WILLIAM S. TILGHMAN, a citizen of the United States, residing in the county of Worcester, (P.O. address Salisbury,) 5 and State of Maryland, have invented certain new and useful Improvements in Fodder-Holders, of which the following is a specification, reference being had to the accompanying drawing.

10 The object of my invention is to provide a corn-fodder holder—an instrument to facilitate the gathering of fodder.

The construction of the instrument and its 15 operation will first be described and the invention then designated in the claim.

In the drawing hereto annexed the instrument is illustrated in perspective.

The letter A designates a wood bar, which in practice should be about eighteen inches 20 long, and, say, one inch by five-eighths in cross-section. The upper end of this bar is provided with a curved or segment-shaped block, B, which by its shape is adapted to rest against the human body, to which it is designed to be 25 attached by means of a belt or strap, C, to pass around the waist. An iron rod, d, has one end securely fastened to the upper end of the wood bar, as at d'. From thence the rod extends straight down the bar, say, two-thirds 30 of its length, at which point the rod is again fastened to the bar by a staple, d², or other suitable device. From this point the rod is curved, as at d³, and bent upward, extending straight and parallel with the part which is 35 attached to the wood bar, the two straight portions with the curved part resembling generally the shape of a letter U. The upper free end of the rod d is provided with a vertical slot, e, formed by a wire, e', secured thereto.

40 A wire, f, is in the present instance secured at one end to the wood bar. From its point of attachment it extends up along the free side of the rod d and passes through the slot e in the upper end of the rod, and has an angular or elbow-shaped bend, f', which normally is in 45 contact with the upper end of the wood bar. This wire serves as a spring, and the elbow-

shaped bend may be pressed away from the wood bar until the elbow part is in contact with the top of the slot e.

50

A follower plate or block, G, has at each end a groove or notch, h, one of which sets astride of and slides on one of the vertical straight portions of the rod d, which thus serve as guides. A piece of hoop-iron is bent 55 in the middle to form a loop, i, and two straight parallel ends, k, whose extremities are rigidly fastened to the follower G. The loop is below the curved part d³ of the rod, and the follower about it, while one of the two straight ends 60 k of the iron are on each side of the said curved part of the rod. This arrangement permits the follower to be raised and lowered while the hoop-iron loop travels astride of the curved part of the rod, and said loop i, by 65 coming against the curved part d³, limits the upward movement of the follower. The spiral spring n surrounds the two straight parallel ends k, one end of the spring resting upon the top side of the curved part of the rod and the 70 other end resting against the lower side of the follower. This spring serves to press the follower upward.

The strap C being buckled around the waist just above the hips, the instrument is used as 75 follows: Both hands of the person using the instrument are free to strip off the fodder, which, as fast as gathered, is placed in the holder above the elbow-shaped bend of the wire spring and pressed down below to the follower, the downward pressure of the fodder 80 being all that is needed to operate the instrument. As the bundle of fodder increases the follower is gradually depressed until the U-shaped-rod holder is full. The entire bundle 85 may then be lifted out by raising it against the elbow-shaped part, which yields for that purpose.

By means of this instrument a person can 90 employ both hands in stripping the fodder from the standing cornstalk, and pass on and continue gathering until a bundle has accumulated, and thereby it is found to greatly facilitate the operation.

Having described my invention, I claim and desire to secure by Letters Patent of the United States—

An instrument to facilitate gathering fodder, consisting of a holder having two straight parallel sides, a spring-actuated follower moving in the said two sides and constituting the bottom of the holder, a spring-actuated device to close the top of the holder above

the follower, and means, substantially as described, for attachment to the human body, as set forth.

In testimony whereof I affix my signature in presence of two witnesses.

WILLIAM S. TILGHMAN.
